ATTORNEYS.

UNITED STATES PATENT OFFICE

CHARLES E. NEGLEY, OF LOS ANGELES, CALIFORNIA

VALVE LIFTER

Application filed April 8, 1927. Serial No. 182,009.

This invention relates to valve lifters, and has for an object the provision of a device which is efficient in operation, easy to handle, readily adjustable, and generally superior in use and service.

Another object is the provision of a valve lifter which is adaptable for any type of valve, and which is so constructed as to permit any degree of lift desired for the said valve.

Other objects will be set forth as the specification proceeds, and with the above and other objects in view the invention consists in the novel and useful provision, formation, construction, association and interrelation of parts, members and features, all as shown in a certain embodiment in the accompanying drawing, described generally, and more particularly pointed out in the claim.

In the drawing:

Fig. 1 is a side elevation of the improved valve lifter shown in operation;

Fig. 2 is an enlarged side elevation of the said valve lifter;

Fig. 3 is a sectional view on the line 3—3 of Fig. 2;

Fig. 4 is a sectional view on the line 4—4 of Fig. 2; and

Fig. 5 is a plan view showing the construction of certain elements of the invention and looking in the direction of the arrow 5 of Fig. 2.

Corresponding parts in all the figures are designated by the same reference characters.

It is perhaps unnecessary to detail the purpose of a valve lifter, save and except that some means must be utilized at times whereby the valve may be lifted against compression of a spring, so that the spring can be released and the valve removed from its guide. The valve spring is usually confined as between a cup secured to the valve stem and the valve guide bushing, said spring urging the valve to seated position. When it is desired to release the valve for various purposes, such as valve grinding, or to replace the spring, the spring must be lifted, and this is ordinarily accomplished by some form of valve lifter which engages beneath the cup on the valve stem to elevate the spring

sufficiently to release the cup from the stem.

Referring now with particularity to the drawing, the improved valve lifter is designated as an entirety by A, and the same includes what may be termed a head bar a, a lift bar b, both of which are adjustably mounted upon a bar c, and means d adapted to cooperate with the lift bar b to perform the function intended by this device. The bar c may be of any cross section, and the head bar a and the lift bar b are both constructed so as to be permitted relative movement on the said bar c. In particular, the lift bar b is formed by utilizing two elongated metal bars 1 and 2, which are secured together for a portion of their length, as indicated at 3, then separated at 4 so as to surround the bar c, there being a set screw 5 seated in the bar b for engaging the bar c whereby the said bar b may be secured against movement relative to the bar c. The bars 1 and 2 separate as shown at 6 the degree of separation being regulated by means 7, constituting a screw passed through a threaded opening in the said bars 1 and 2. There are many ways of causing separation between the bars 1 and 2 at the portion 6, such as by proving one of said bars with a screw-threaded opening, the other of said bars having a plain opening, then adjusting a nut 8 on said screw, which nut is included between the said bars. The said bars 1 and 2 outwardly from the said adjusting screw are parallel at the zone 9. Thus what may be termed a fork is provided.

Likewise in the drawing it will be seen that the portion 9 of said bars is reduced as to width, as shown in Fig. 2 at 10. The bar b is provided with upper and lower lips 11 and 12, which act as guides to prevent up and down play of said lift bar relative to the bar c.

The head bar a likewise comprises two bars 13 and 14, joined together, and spaced apart at one end 15, so as to surround the bar c, there being a set screw 16 seated in the head bar a for engaging the bar c whereby the head bar may be adjustably secured to the bar c. The opposite end is ring shaped at 17. The said bars 13 and 14 are provided

with lips 18 and 19, which act as guides for the head bar, functioning the same as the lips 11 and 12.

The means *d* comprises a device adapted to be reciprocated in such a manner as to cooperate with the lifting bar to lift the spring of the valve. This means in the present instance comprises a tube 20 which is split for a portion at 21, so as to receive the cam head 22 of a lever 23. Within the bore of the tube is placed a bearing member 24, and the head of a plunger 25 engages said bearing. In order to maintain the plunger head in contact with the bearing a coil spring 26 surrounds the plunger and engages said head, the coil spring being held within the bore through the medium of an annular bushing 27. The cam head 22 is rotatively secured within the split portion of the tube by a pin 28. The cam head is curved, as shown at 29, and provided with a substantially flat nose 30. The arm 23 forms a continuation of the head. When the arm 23 is at right angles, or substantially so, to the head bar *a* the plunger has been moved its maximum distance outwardly from the tube 20, and when the arm is revolved upwardly the bearing 24 will ride along the curved surface 29 and the plunger will be retracted within the tube 20 under urgency of the spring 26.

In actual operation reference is had to Fig. 1, and it will be seen that the fork ends 9 of the lift bar have engaged beneath the cup 30 of the spring 31 surrounding the valve stem. The plunger 25 engages the valve head, and when the lever is pushed downwardly the spring is compressed, as shown. Adjustment can be made for any size of valve or degree of movement desired by regulating the spacing of the head and lift bars *a* and *b* relative to the bar *c*. A small pin 32 in the valve stem may be knocked therefrom so that upon releasing the lever 23 the spring cup will drop downwardly from the valve stem, so that the valve can be removed.

The device is compact, and very efficient and easy to handle. When the nose is engaging the bearing 24 the device is locked against movement, and the operator can confine his attention to removing the pin 32, or performing any other work desired.

It is obvious that various changes and modifications and variations may be made in practising the invention in departure from the particular showing of the drawing, without departing from the true spirit thereof.

Having thus disclosed my invention, I claim and desire to secure by Letters Patent: 60 A valve lifter of the character disclosed including a supporting bar, a lift bar movable thereon, said lift bar comprising a pair of members adapted to separate adjacent one end and formed to surround the supporting bar at the opposite end, means for regulating

the degree of separation of said two members of the lift bar, and further means for guiding movement of the lift bar upon the supporting bar.

In testimony whereof, I have signed my name to this specification.

CHARLES E. NEGLEY.
